US00D402032S

United States Patent [19]

Stone

[11] Patent Number: **Des. 402,032**
 [45] Date of Patent: ****Dec. 1, 1998**

[54] **NEURO GAP PLATE FOR
OSTEOSYNTHESIS**

[75] Inventor: **Kevin T. Stone**, Warsaw, Ind.

[73] Assignee: **Walter Lorenz Surgical, Inc.**,
Jacksonville, Fla.

[**] Term: **14 Years**

[21] Appl. No.: **51,844**

[22] Filed: **Feb. 20, 1996**

[51] LOC (6) Cl. **24-03**

[52] U.S. Cl. **D24/155**

[58] Field of Search **D24/155; 606/69-77**

[57] CLAIM

The ornamental design for a neuro gap plate for osteosynthesis, as shown and described.

DESCRIPTION

FIG. 1 is a perspective view of a first embodiment of a neuro gap plate for osteosynthesis showing my new design;

FIG. 2 is a top view of FIG. 1;

FIG. 3 is a bottom view of FIG. 1;

FIG. 4 is a front view of FIG. 1;

FIG. 5 is a rear view of FIG. 1;

FIG. 6 is a right side view of FIG. 1, with the understanding that the left side view is a mirror image of the right side view;

FIG. 7 is a perspective view of a second embodiment of a neuro gap plate for osteosynthesis;

FIG. 8 is a top view of FIG. 7;

FIG. 9 is a bottom view of FIG. 7;

FIG. 10 is a front view of FIG. 7;

FIG. 11 is a rear view of FIG. 7;

FIG. 12 is a right side view of FIG. 7, with the understanding that the left side view is a mirror image of the right side view;

FIG. 13 is a perspective view of a third embodiment of a neuro gap plate for osteosynthesis;

FIG. 14 is a top view of FIG. 13;
FIG. 15 is a bottom view of FIG. 13;
FIG. 16 is a front view of FIG. 13;
FIG. 17 is a rear view of FIG. 13; and,

FIG. 18 is a right side view of FIG. 13, with the understanding that the left side view is a mirror image of the right side view.
